UNITED STATES PATENT OFFICE.

OLIVER M. CAMPBELL, OF VAN BUREN, ARKANSAS.

REFRIGERATOR.

933,059.

Specification of Letters Patent.

Patented Sept. 7, 1909.

Application filed March 20, 1908. Serial No. 422,328.

To all whom it may concern:

Be it known that I, OLIVER M. CAMPBELL, a citizen of the United States, and a resident of Van Buren, in the county of Crawford and State of Arkansas, have invented 5 a new and useful Improvement in Refrigerators, of which the following is a specification.

This invention relates to portable or sectional refrigerators, and has for its object 10 to provide novel details of construction for a refrigerator, that will render it very convenient, insure proper circulation of cold, dry air throughout the interior of the refrigerator, prevent sweaty deposits of moisture 15 on the walls within the refrigerating chamber, and afford perfect drainage for water formed by melting of ice used as a refrigerant.

20 The invention consists in the novel construction and combination of parts, as is hereinafter fully described and defined in the appended claims.

Reference is to be had to the accompanying 25 drawings forming a part of this specification, in which similar characters of reference indicate corresponding parts in all the views.

Figure 1 is a vertical sectional view substantially on the line 1—1 in Fig. 2. Fig. 2 is a vertical sectional view of the upper portion of the refrigerator, taken at right angles to the plane of the section-line 1—1, and substantially on the line 2—2 in Fig. 1. 35 Fig. 3 is a detached perspective view partly in section showing the drip pan, its supports, and a novel draining device for the water dripping from the ice that is supported by the pan. Fig. 4 is a section on line 4—4 of Fig. 3, and Fig. 5 is a perspective view of a portion of the inner frame work of the pan, parts being broken away.

The refrigerator body is essentially rectangular and consists of four side walls 5, a top wall 5^a and a bottom wall 5^b. These walls are each preferably formed with intercellular spaces, filled with any suitable non-conductor of heat, as usual in well constructed devices of this character. It will be noted that the top wall 5^a and the bottom wall 5^b are both firmly affixed upon respective ends of the side walls 5. In one side wall 5 a rectangular opening is formed near the top wall 5^a, and in said opening a door 5^c is closely fitted and hinged, so as to be

adapted for outward swinging movement when access to the interior of the body is desired. In another side wall 5, near the bottom wall 5^b, a larger rectangular opening is produced, wherein is closely fitted a door 5^d, that is also hinged upon the body, so as to be swung outward and give access to the interior of a refrigerating chamber A, that will be further mentioned hereinafter.

Within the refrigerator and below the ice compartment is arranged my improved drip-pan 6, which consists of a hollow body having at one longitudinal edge a drain trough 6^a, the upper edge of the outer wall of which 65 is in the same horizontal plane as the bottom of the pan, so that the air will not be obstructed in its passage over the pan to the storage compartment of the refrigerator. The pan is preferably constructed as follows: Four timbers a of the same width are 70 joined together at their ends to form a rectangular frame, between the side timbers of which extend the cross pieces a' so as to brace and strengthen the same. Upon the 75 upper face of this frame I place paper a² or other non-conductor of heat and over this paper and secured to the frame is the top a³, which is preferably formed of tongued and grooved boards. A piece of scantling or 80 other timber a⁴, having its upper edge beveled or inclined from one end to the other, is then secured to one of the side timbers a. I then surround the frame thus constructed 85 with four boards a⁵, three of which are of a width to extend above the top a² to form a ledge, while the other one is of a width that its upper edge is on a level with the bottom 90 of the pan and forms with one of the side timbers a and the timber a⁴ a drain trough 95 6^a. Upon the lower face of this frame I place paper a⁶ or other non-conductor and over the paper and secured to the frame is the bottom a⁷ preferably formed of tongued and grooved boards. The pan is completed 100 by a facing a⁸ of galvanized iron or other rust-proof sheet metal for the top of the frame and the trough, the facing being secured to the upper edges of the boards a⁵. The area of this drip-pan body is so relatively proportioned, that when in position a suitable space will be afforded between the sides thereof and the corresponding side walls 5 of the refrigerator body.

Preferably for large refrigerators the 110 drip-pan 6 is hung from the top wall 5^a by a plurality of suspension-rods 7, which at

their lower ends are secured upon the side walls of the pan. The upper ends of the rods 7 pass through the top wall 5^a, and reinforce strips 5^e thereon, that adapt the rods for receiving washers and nuts *c*, thus hanging the pan from the top wall, as shown in Figs. 1 and 2, centrally in the body of the refrigerator. The pan, as shown in the drawings, is supported by bracket strips *h*, which in turn are supported at the ends by uprights *h'* extending to the floor. Preferably the pan 6 is disposed somewhat above the lower door 5^d and is given a slight inclination from a horizontal plane.

15 Upon the upper side of the drip-pan 6 a number of batten strips *i* are seated at suitable distances apart, each strip being divided into sections, three in number in this case, and each sectional batten-strip is tapered 20 longitudinally a degree that will render the upper sides of these sectional strips horizontal when all are seated upon the upper surface of the drip-pan. Upon corresponding sections of the batten-strip *i* a plurality 25 of slats *m* are affixed, which are spaced apart parallel with each other, and when in position produce a slatted tray that covers the drip-pan, said tray receiving the ice that is placed in the upper portion B of the refrigerator body, through the doorway having the door 5^c as a closure. The slatted tray is 30 level on the upper side, so that ice will remain without slipping where it is placed, thus permitting the even storage of ice in the 35 ice-chamber, while the waste water and chilled air will pass down between the slats *m* over the bottom of the pan to the trough 6^a, and thence to the drain pipe *g*, the water passing into the trough 6^a, and the air to 40 the storage compartment. By constructing the slatted tray in sections, convenience is afforded for handling the same when the tray is placed within or removed from the ice-chamber B, which is necessary to enable 45 a thorough cleansing of the refrigerator at proper times.

Upon the side boards *a⁵* of the pan the lower ends of bars *n'* of a slatted rack *n* is seated, as indicated in Fig. 1, said rack being 50 further supported by the suspension-rods 7, whereon it is detachably held by clip-bands *o* or other means. Upon two of the other side walls of the ice-chamber B, and also on the door 5^c, corrugated guard-walls *p* and *p'* 55 of wood or metal are secured, and the guard wall *p'* thereof, that is opposite to the slatted rack *n*, rests upon the front board *a⁵* of the pan and is held upright by clips *o'*, which engage the adjacent pendent suspension-rods 7.

By the provision of the corrugated guard-walls and the slatted rack *n*, the lining-walls of the ice-chamber B are preserved from injury, and the ice is kept from contact with the walls proper and a circulation of air is

permitted between the slats, thus keeping the walls in a dry condition.

It will be seen that air from the chamber A, below the ice-chamber B, if warmed, will pass up between the inner surface of the side 70 wall of said ice-chamber and the guard-wall *p'*, and thence down through the ice in the chamber B, across the same and through the slatted racks *n* and *m*, the air thus cooled descending into the lower chamber A and 75 displacing warmer air. The cold air will descend to the bottom of the chamber A and produce a low degree of temperature for the preservation of the food in the storage compartment; and it will be evident that the 80 constant circulation of cold, dry air currents as stated will render the temperature in the lower chamber A uniformly cold and dry.

It will be seen that the novel construction of the improvement facilitates rapid, and 85 proper circulation of the air, and adapts the parts thereof for renewal as long service may require.

What I claim is:

1. A drip pan for refrigerators, comprising a rectangular bottom, a frame on the bottom and spaced from the edges thereof, the frame being a greater distance from one edge of the bottom than the other three edges, a top secured upon the frame, a timber having an inclined upper face and secured upon the bottom of the side that projects the farthest beyond the frame and against said frame, boards secured upon the bottom and frame at three sides and projecting above the same, a board secured to the bottom at the fourth side thereof and against the said timber, the said board forming with the timber and frame a trough and having its upper edge in the same horizontal plane 100 with the top, and a metallic facing for the top and trough.

2. A drip pan for refrigerators, comprising a frame having cross pieces, a top of paper and boards secured to the frame, a timber having an inclined upper face and secured to one side of the frame, boards secured to the frame and to the said timber, three of the boards extending above the top to form a ledge, and the fourth board terminating on a level with the said top and forming with the frame and the said timber a drain trough, a bottom of paper and boards secured to the said frame, timber and boards, and a metallic facing for the top and trough.

3. In a refrigerator having a rectangular body, the combination therewith, of a drip pan, means for supporting the pan in the said body, a slatted tray supported on the said pan above the bottom thereof, upright 125 corrugated guard-walls on three of the sides of the body, an upright slatted rack on the fourth side of the body, and means for supporting the slatted rack and the guard wall opposite the said rack upon the pan with 130

their upper ends a short distance from the top of the body and spaced from the side walls of said body.

4. In a refrigerator having a rectangular body, the combination therewith of a drip pan, rods supporting the pan from the refrigerator body, a slatted tray on the drip pan, an upright corrugated guard-wall supported above one end of the slatted tray by

attachment to certain of the suspending rods, ¹⁰ and an upright slatted rack mounted upon the opposite end of the tray and secured detachably upon the remaining pan supporting rods.

OLIVER M. CAMPBELL.
